MAGNETICALLY CONTROLLED GASEOUS
DISCHARGE DEVICEPercy L. Spencer, West Newton, Mass., assignor
to Raytheon Manufacturing Company, Newton,
Mass., a corporation of Delaware

Application February 11, 1938, Serial No. 190,007

7 Claims. (CL. 250—27.5)

This invention relates to controlled gaseous discharge devices, and more particularly to such devices in which the time of starting of an ionizing discharge between the electrodes is controlled by means of a magnetic field.

An object of my invention is to provide such a magnetically controlled tube which is capable of conducting and controlling large values of currents flowing in either or both directions through said tube under substantial applied voltages.

Another object of this invention is to produce such a device which is flexible in control and which is adapted to accomplish a wide variety of control operations.

The foregoing and other objects of my invention will be best understood from the following description of an exemplification thereof, reference being had to the accompanying drawings wherein:

Fig. 1 is a cross-sectional view of one embodiment of my invention showing my novel discharge tube together with a diagrammatic representation of a circuit which may be used therewith; and

Figs. 2, 3 and 4 are diagrammatic representations of various types of control current supply for Fig. 1.

In Fig. 1, 1 represents a hermetically sealed envelope, preferably of glass, having enlarged end chambers 2 at each end thereof, said enlarged chambers being connected by a tubular intermediate section 3. In each enlarged chamber 2 is mounted a cathode 4. Adjacent each cathode 4 and surrounding the discharge path terminating at said electrodes is an intermediate control electrode 5. The electrode 5 is preferably made of non-magnetic material, and may comprise a cylinder of sheet metal, such as non-magnetic nickel, tantalum or carbon. Since each electrode 5 will also operate as an anode, as will be hereinafter described, it is preferred that the material of which the electrode 5 is constituted shall be relatively refractory. The electrodes 5, as shown, are each provided with an end plate 6 having a relatively large opening 7 passing therethrough. The opening 7 therefore permits a discharge to pass from each cathode 4 through the adjacent opening 7 to the opposite electrode 5 as an anode. Of course each electrode 5 may be of any other suitable form, and it is possible to make it so that it does not completely surround the discharge path but only partially surrounds it. In the specification and claims, whenever the electrode 5 is defined as surrounding the discharge path or when the discharge is described as

passing through the electrode 5, it is intended that these expressions shall include those conditions in which the electrode 5 partially surrounds the discharge path to an extent sufficient to accomplish the type of control hereinafter described.

The envelope 1 is provided with a reentrant stem 8 at each end thereof, each of which stems supports one of the cathodes 4 and one of the intermediate electrodes 5. Each cathode 4 preferably consists of a hollow member 9, preferably of some metal such as nickel provided with a plurality of internal radially disposed metal fins 10. The metal fins and also the interior of the hollow member 9 are coated with an electron-emissive material, such as, for example, alkaline earth oxides. In order to heat the coated surfaces of the cathode 4 to temperature of thermionic emission, a heating filament 11 is disposed within the hollow member 9. The heating filament 11 may consist of a single helix of a refractory conductor, such as tungsten, and is electrically connected at its upper end to the hollow member 9 by being welded to one of the fins 10. In order to prevent excessive radiation of heat from the hollow member 9, it is surrounded by means of a heat shield 12. Each cathode assembly 4 is supported on the stem 8 by means of a pair of conducting standards 13 which are sealed in the press 8. One of the standards 13 is sealed through said press so as to provide an external electrical connection to the cathode 4. The lower end of the heating filament 11 is provided with a lead 14 which is likewise sealed through the press 8 so as to provide an external electrical connection thereto. In the drawings it will be seen that the cathode 4 at the right-hand end is shown in cross-section. However, it is to be understood that the cathode 4 at the left is of identically the same structure as that shown at the right-hand end.

In order to support each of the intermediate electrodes 5 in position adjacent each cathode 4, each electrode 5 is provided with a pair of conducting standards 15, which are sealed in the respective press 8. In each case one of the standards 15 is sealed through its press 8 so as to provide an external electrical connection to its associated electrode 5.

The envelope 1 containing the construction as described above, after being thoroughly evacuated in accordance with the usual practice, is filled with some suitable ionizable medium. This medium may be a metallic vapor, such as mercury vapor, or a gas, such as one of the noble gases, or a mixture thereof. When mercury vapor is

used, pressures in the range of one to one hundred microns are preferred, while in the case of a noble gas, such as argon, a pressure of the order of one millimeter or less is preferred. In any event, the 5 gas preferably is of a suitable value so that when a discharge across the gas or vapor becomes ionized, a current flows at a relatively low voltage drop.

In order to supply power to the device, there 10 is provided a supply transformer 16 having a primary 17 and a secondary 18. The primary 17 is adapted to be connected to some suitable source of alternating current. A conductor 19 connects one end of the secondary 18 to one of the leads 15 13, and thus to one of the cathodes 4, for example the right-hand cathode. A conductor 20 extends from the opposite end of the secondary 18 to a load 21. The other side of the load is connected by means of a lead 22 to the other conductor 13, and thus to the other cathode 4. Each pair of conductors 13 and 14 is adapted to 20 be connected to a suitable source of heating current, whereby the heating filament 11 in each case is raised to its operating temperature. The 25 external conductor 15 of each intermediate electrode 5 is connected by means of a conductor 15' to the adjacent lead 13, and in this way each intermediate electrode 5 is connected to its adjacent cathode 4.

30 Upon supplying heating current to each pair of conductors 13 and 14, the filament 11 and consequently the coated surfaces of each cathode 4 will be raised to a temperature at which said coated surfaces emit a copious supply of electrons 35 thermionically. As each cathode 4 becomes negative, the electrode 5 associated with the opposite cathode 4 will become positive, and thus will act as an anode with respect to the negative cathode. Under these conditions, the electrons 40 emitted from the negative cathode will flow through its adjacent electrode 5, through its discharge opening 7 to the opposite electrode 5. This flow of electrons will produce intense ionization of the gas within the envelope, and current at a relatively low voltage drop will flow 45 between the negative cathode 4 and the positive electrode 5. Since these conditions are reversed with each reversal of the applied voltage, it will be seen that currents will flow through the tube 50 in both directions, and an alternating current will be delivered to the load 21.

As more fully described and claimed in my copending application, Serial No. 612,235, filed May 19, 1932, now Patent No. 2,124,682, for an improvement in Electrical gaseous discharge devices, a discharge of the type which I have described above is prevented from starting when a magnetic field of a predetermined magnitude, intercepting the direction of said discharge, is impressed across the space within the intermediate electrode 5. This transverse magnetic field may be applied in any suitable manner. For example, I have shown a pair of magnetic pole pieces 23 disposed on opposite sides of each intermediate electrode 5 outside of the tubular portion 3. Each pair of pole pieces 23 may form part of a unitary core structure. In order to energize each of said core structures and said magnetic pole pieces, energizing or control coils 24 are provided 65 for each of the pole pieces 23. The energizing coils 24 associated with each pair of pole pieces 23 are fed with current through a control device 25 which may be energized from any suitable source. As indicated in the drawings, this source 70 75 may be the transformer 16. In this case a pair

of conductors 26 are provided connecting the input to each control device 25 in parallel, and a pair of conductors 27 connect the two leads 26 to opposite sides of the secondary winding 18. Although I have described each intermediate electrode 5 as being provided with a separate pair of pole pieces, a single pair of pole pieces could be provided if such a magnetic structure were made sufficiently large to set up a transverse magnetic field in the space within both of the 10 intermediate electrodes 5. However, in the interest of more flexible control, the construction as described in the drawings is preferred.

When the device is energized, as described above, and a discharge tends to flow alternately 15 from each cathode 4 to the opposite electrode 5, it will be seen that such a discharge must pass through the intermediate electrode adjacent its associated cathode. Under these conditions, when a magnetic field is set up by each pair of 20 pole pieces 23 intercepting the discharge passing through said intermediate electrode 5, the initiation of the discharge will be delayed for a pre-determined part of the voltage cycle, depending upon the relative value of the magnetic field and 25 the applied voltage. In most instances the discharge can be considered as being initiated whenever the magnetic field falls to substantially a zero value. In order to accomplish different types of control, the control devices 25 may be 30 constructed, for example, to supply to the coils 24 a controllable direct current, as indicated in Fig. 2. Also each control device 25 might be constructed to supply to the energizing coils 24 a 35 variable current of the same frequency as that supplied to the transformer 16. One arrangement might be that indicated in Fig. 3 wherein each control device 25 would be constructed so as to shift the phase of the current supplied to the coils 24 with respect to the voltage supplied to the transformer 16. Another arrangement might be to construct each control device 25 as an adjustable resistor, as indicated in Fig. 4, whereby alternating current varying in magnitude 40 would be supplied to the coils 24.

The resultant variations in the output of a tube of the general type which I have described which are accomplished by these various types of control are fully described and claimed in my copending application mentioned above, and also in my copending application, Serial No. 188,887, filed February 5, 1938, for an improvement in Controlled gaseous discharge devices. Briefly these types of controls might be summarized as follows. When variable amounts of direct current are supplied to the coils 24, (Fig. 2) alternating currents will flow in the load 21 and will be controlled in magnitude. When alternating current varying in phase (Fig. 3) or magnitude (Fig. 4) is supplied to the coils 24, likewise alternating current of varying magnitude will be supplied to the load 21. One type of control is that in which magnetic pole pieces 23 are biased with a certain amount of unidirectional flux, either by being constructed as a permanent magnet or by having the coils 24 supplied with a direct current component, and in addition being supplied with an alternating component of flux by feeding an alternating component of current to the coils 24. Under these conditions, the device may be made to supply rectified current to the load 21, the polarity of said direct current depending upon the phase relationship of the alternating current component of the flux with respect to the voltage applied to the tube. Fur- 50 55 60 65 70 75 80 85 90 95 100

thermore, under these conditions, variation in said phase relationship will produce variation in the magnitude of the direct current supplied to the load.

5 This invention is not limited to the particular details of construction or operation as described above as many equivalents will suggest themselves to those skilled in the art. For example, the electrodes can take a variety of forms. Furthermore, various combinations of circuits and controls may be impressed upon the tube, producing a wide variety of devices of operation. It is accordingly desired, therefore, that the equivalents which come within the scope of the appended claims be considered as being included within the scope of the invention.

What is claimed is:

1. In combination, an electrical space discharge device comprising an envelope containing an ionizable atmosphere, two cathodes, two intermediate electrodes, each adjacent one of said cathodes, each intermediate electrode having a discharge passage through it in the direction of the other of said intermediate electrodes, whereby a discharge may pass from each cathode past one of said intermediate electrodes to the other of said intermediate electrodes as an anode, and means for producing a magnetic field which is transverse to the direction of each of said discharges adjacent each intermediate electrode.
2. In combination, an electrical space discharge device comprising an envelope containing an ionizable atmosphere, two thermionic cathodes, two intermediate electrodes, each adjacent one of said cathodes, each intermediate electrode having a discharge passage through it in the direction of the other of said intermediate electrodes, whereby a discharge may pass from each cathode past one of said intermediate electrodes to the other of said intermediate electrodes as an anode, and means for producing a magnetic field which is transverse to the direction of each of said discharges adjacent each intermediate electrode.
3. In combination, an electrical space discharge device comprising an envelope containing an ionizable atmosphere, two thermionic cathodes, two intermediate electrodes, each adjacent one of said cathodes, each of said intermediate electrodes being connected to its adjacent cathode, each intermediate electrode having a discharge passage through it in the direction of the other of said intermediate electrodes, whereby a discharge may pass from each cathode past one of said intermediate electrodes to the other of said intermediate electrodes as an anode, and means for producing a magnetic field which is transverse to the direction of each of said discharges adjacent each intermediate electrode.
4. In combination, an electrical space discharge device comprising an envelope containing an ionizable atmosphere, two thermionic cathodes, two intermediate electrodes, each adjacent

one of said cathodes, each of said intermediate electrodes being connected to its adjacent cathode, each intermediate electrode having a discharge passage through it in the direction of the other of said intermediate electrodes, whereby a discharge may pass from each cathode past one of said intermediate electrodes to the other of said intermediate electrodes as an anode, means for producing a magnetic field which is transverse to the direction of each of said discharges adjacent each intermediate electrode.

5. In combination, an electrical space discharge device comprising an envelope containing an ionizable atmosphere, two thermionic cathodes, two intermediate electrodes, each adjacent one of said cathodes, each intermediate electrode having a discharge passage through it in the direction of the other of said intermediate electrodes, whereby a discharge may pass from each cathode past one of said intermediate electrodes to the other of said intermediate electrodes as an anode, means for producing a magnetic field which is transverse to the direction of each of said discharges adjacent each intermediate electrode, and means for controlling said magnetic fields for controlling said discharges.

6. In combination, an electrical space discharge device comprising an envelope containing an ionizable atmosphere, two thermionic cathodes, two intermediate electrodes, each adjacent one of said cathodes, each intermediate electrode having a discharge passage through it in the direction of the other of said intermediate electrodes, whereby a discharge may pass from each cathode past one of said intermediate electrodes to the other of said intermediate electrodes as an anode, means for producing a magnetic field which is transverse to the direction of each of said discharges adjacent each intermediate electrode, and means for controlling the magnitude of said magnetic fields for controlling said discharges.

7. In combination, an electrical space discharge device comprising an envelope containing an ionizable atmosphere, two thermionic cathodes, two intermediate electrodes, each adjacent one of said cathodes, each of said intermediate electrodes being connected to its adjacent cathode, each intermediate electrode having a discharge passage through it in the direction of the other of said intermediate electrodes, whereby a discharge may pass from each cathode past one of said intermediate electrodes to the other of said intermediate electrodes as an anode, means for producing a varying magnetic field which is transverse to the direction of each of said discharges adjacent each intermediate electrode, means for connecting a source of alternating current between said cathodes, and means for controlling the phase angles between said magnetic fields and said source for controlling said discharges.

PERCY L. SPENCER.
